[57] **CLAIM**

The ornamental design for an oxygen analyzer housing, as shown.

DESCRIPTION

FIG. 1 is a left front perspective view of an oxygen analyzer housing showing my new design; FIG. 2 is a front elevational view thereof;

FIG. 3 is a left side elevational view thereof, the right side being a mirror image thereto;

FIG. 4 is a top plan view thereof;

FIG. 5 is a rear elevational view thereof; and

FIG. 6 is a bottom plan view thereof.
